(57) **CLAIM**

The ornamental design for a skylight for a portable shelter, as
shown and described.

DESCRIPTION

FIG. 1 is a front, right perspective view of a skylight for a
portable shelter in accordance with the present invention;

FIG. 2 is a front, elevation view thereof;

FIG. 3 is a top, plan view thereof;

FIG. 4 is a right side, elevation view thereof;

FIG. 5 is a back, elevation view thereof; and,

FIG. 6 is a left side, elevation view thereof.

The broken lines showing a possible portable shelter structure
with possible window and door openings and possible support
structures are for illustrative purposes only and form no
part of the claimed design.
